CHARLES C. GALE, OF INDIANAPOLIS, INDIANA.

Letters Patent No. 104,441, dated June 21, 1870.

IMPROVEMENT IN SHIELDS FOR PADLOCKS.

The Schedule referred to in these Letters Patent and making part of the same.

I, CHARLES C. GALE, of Indianapolis, in the county of Marion and State of Indiana, have invented certain Improvements in Shields for Padlocks, of which the following is a specification.

This invention relates to a shield or shell made of cast metal, glass, or other suitable inflexible but frangible material, for self-fastening locks, adapted to inclose the entire lock-case, and so constructed that the staple, or other object through which the shackle passes, will prevent the movement or removal of the shield intact while the lock remains secured, the purpose being to ascertain whether the lock has been tampered with by unauthorized persons, which will be evident if the shield is broken. The shield renders the key-hole wholly inaccessible until the shell is broken, which is easily done by the proper officer. It is preferable to make the shield of cast metal or glass, so that, in removing the same, a noise will be caused, whereby the detection of the intruder is or may be facilitated. The invention, although capable of general application, is especially intended for the locks of freight cars.

In the drawing—

Figure 1 is a side view.

A is a padlock, of the usual size or pattern, used for locking railway cars, or other kindred purposes.

B is a shield, made of glass, metal, or suitable material, open at the bottom, and having an opening at the top sufficiently large to permit the staple of the lock to protrude.

The top corners are curved inward, so as to form a shoulder resting upon the upper side of the lock, and cannot pass down over it.

The form or design of the shield may be varied to

suit the taste or circumstances, the main object being to provide a shield to cover the key-holes of padlocks, to render them inaccessible except as herein provided.

This shield envelops the lock, effectually covering the key-hole, and when the lock is secured to the staple in the ears, the shield cannot be removed for unlocking without first breaking and destroying the same.

If the shield should be found broken or missing, except it be done by the proper person, it will readily indicate that the lock has been tampered with.

By this means, any improper meddling with the locks of cars may be readily traced and the perpetrator discovered.

I prefer to use shields made of thin cast-iron, as the destruction of the same cannot be accomplished without causing more or less noise, whereby the detection of any one tampering with the lock is materially assisted.

When the proper person desires to unlock the cars, a light weight is held under or behind the shield, which is then struck a light blow on the opposite side, and the shield is fractured and falls in pieces.

I claim—

A shield, B, made substantially as described, entirely covering the lock-case, and secured by the staple through which the shackle passes, whereby the key-hole, when the lock is secured, is rendered wholly inaccessible until the shield is broken and destroyed, as herein set forth.

C. C. GALE.
